UNITED STATES PATENT OFFICE.

CHARLES LINFORD, OF PITTSBURG, PENNSYLVANIA.

INCREASING AND REDUCING JOINT FOR ELECTRIC-WIRE CONDUITS.

SPECIFICATION forming part of Letters Patent No. 268,031, dated November 28, 1882.

Application filed February 15, 1882. (No model.)

To all whom it may concern:

Be it known that I, CHAS. LINFORD, a citizen of the United States, residing at Pittsburgh, in the county of Allegheny and State of Pennsylvania, have invented certain new and useful Improvements in Increasing and Reducing Joints for Electric-Wire Conduits; and I do hereby declare the following to be a full, clear, and exact description of the same, reference being had to the accompanying drawings, in which—

Figure 1 is a side elevation of an increasing and reducing joint illustrating my invention, and Fig. 2 is a longitudinal section of the same.

Like letters refer to like parts wherever they occur.

The main objects to be obtained in joints for electric-wire conduits is to insure perfect insulation, and thus avoid the effect of earth-currents, and at the same time have the construction such that ready access can be had to the interior of the conduit for the purpose of leading off any required number of surface-wires. These results I obtain by means of what I term an "increasing and reducing joint," or one where two conduits of different diameters or cross-sectional areas are connected by flanged coupling collars or bands pierced by one or more orifices for the passage of a surface wire or wires.

I will now proceed to describe my invention, so that others skilled in the art to which it appertains may apply the same.

In the drawings, A indicates a conduit-section tube for the reception of the wires, which tube may be of any desired cross-section or size, but is preferably cylindrical, because such form is most readily produced and fitted up. Within the tube A are arranged any desired number of glass insulating-tubes a for the electric wires. These glass tubes a are supported by perforated disks b, which may be made of paper, pasteboard, or other suitable non-conducting material, and serve to separate the glass tubes a from each other and from the walls of conduit A. The space c between the glass tubes a may be filled with paraffine, bitumen, or other non-conducting material, preferably of a character that can be liquefied by heat and will become solid on cooling.

On the extremity of the conduit-section A is secured a coupling-collar, having flange B, preferably by means of a screw-thread, a', in the collar, as shown, though any approved method may be adopted, and said flange is 55 preferably provided with an annular depression or countersunk seat, b', for the reception of a packing, and with bolt-holes for the reception of the bolts by which the parts are secured.

C indicates a packing which may be employed to close the joint. This packing is of any suitable compressible or resilient non-conducting material adapted to fit within the end of the conduit-section A, perforated for the 65 reception of the ends of the glass insulating-tubes a, and having a lateral flange, c', adapted to fit the annular seat b' of the coupling-flange B.

D indicates a second conduit-section of as 70 much less diameter or cross-sectional area as is required to give space in its coupling-flange for the exit of the desired number of surface-wires. This conduit contains the same glass insulating-tubes, a, perforated separating-disks 75 b, and bitumen or other non-conducting filling in the space c, surrounding the glass insulating-tubes. It is also provided with a compressible or resilient non-conducting packing, C', which projects slightly beyond the end of 80 the conduit D, but need not necessarily have the lateral flange, as in the case of packing C.

B' indicates the coupling-flange for section D, to which it is secured by a screw-thread, a², within its collar, as shown, or in other 85 suitable manner. This flange is preferably formed with an annular rib or projection, b², the counterpart of the seat b' on the opposite coupling-flange, and has perforations or notches s corresponding in number to the number of 90 surface-wires it is desired to lead off.

m and n indicate bolts and nuts, which may be used for forcing the coupling-flanges together. In fitting up the flanges the perforations or notches s for the exit of the surface-wires will be made to register with the outer 95 insulating-tubes, a, of the series.

The devices being of the general character specified, the sections of the conduit may be laid in the usual manner, the wires passed 100

- through the glass insulating-tubes *a*, and the connection of the continuous wires made by twisting the ends of the wires. Where a surface-wire is to be conducted off, the usual 5 gutta-percha-covered or other insulated wire selected for that purpose is passed in at the exit hole or notch *s* and connected with one of the wires of the conduit, the surface-wire being drawn in until its insulating-coating 10 fills up and packs in the exit-opening *s*, so that no moisture can enter the joint. If this is not sufficient, other and well-known means may be used to pack the exit-orifice. The coupling-flanges *B* *B'* are then forced tightly together 15 by means of the bolt *m* and nut *n*, and the compression of the flanged packing *C* between the ends of the sections, as well as the compression of packing *C'*, will insure a water-tight joint and perfect insulation of the wires.
- 20 It is evident that the flanges *B* *B'* may be made so thick as to perform the function of and dispense with a distinct collar; but such a construction is not desirable.
- I do not herein claim a conduit consisting 25 of an outer shell or tube, glass insulating-tubes supported by perforated disks, and inclosed by or embedded in paraffine or other non-conducting material. Neither do I herein claim the flanged packing, as I do not intend to limit 30 myself to any special construction of conduit or packing.
- Having thus described my invention, what I claim, and desire to secure by Letters Patent, is—
- 35 1. A coupling for electric-wire conduits, consisting of two inclosing collars or bands, constructed substantially as described, whereby

they may be made to engage the ends of two adjacent sections of the conduit, provided with flanges by which they may be bolted together, 40 the said collars being constructed to engage conduits of different sizes, and the lesser provided with an orifice or orifices for the exit or entrance of one or more conductors, substantially as set forth.

2. A coupling for electric-wire conduits, consisting of two inclosing collars or bands, constructed substantially as described, whereby they may be made to engage the ends of two adjacent sections of a conduit, provided with 50 flanges by which they may be bolted together, the said collars being constructed to engage conduits of different sizes, one of said flanges having a packing-seat and the lesser flange provided with an orifice or orifices for the exit 55 or entrance of one or more conductors, and an interposed flanged compressible or resilient non-conducting packing, substantially as and for the purpose specified.

3. The combination, with the conduits *A* and *D* of unequal cross-sectional area, of the coupling flanged band or collar *B*, having the seat *b'*, the coupling flanged band or collar *B'*, having the projection *b*² and orifice *s*, and the interposed flanged compressible non-conducting 65 packing *C*, substantially as and for the purpose specified.

In testimony whereof I affix my signature, in presence of two witnesses, this 14th day of February, 1882.

CHARLES LINFORD.
